UNITED STATES PATENT OFFICE.

CHARLES POHL, OF LOS ANGELES, CALIFORNIA.

ENGINE-STARTER.

1,149,783.

Specification of Letters Patent. Patented Aug. 10, 1915.

Application filed May 17, 1915. Serial No. 28,606.

To all whom it may concern:

Be it known that I, CHARLES POHL, a citizen of the United States, residing at the city of Los Angeles, in the county of Los Angeles 5 and State of California, have invented new and useful Improvements in Engine-Starters, of which the following is a specification.

My invention relates to a mechanical starter for an explosion engine, particularly 10 designed for use on an automobile, and the object thereof is to produce a starter for the engine which is simple in construction, efficient in operation and which can be easily attached to any of the standard makes of 15 machines without alteration or injury to any of the parts.

A further object is to produce a starter in the use of which a backfire cannot cause injury to the operator and which after each 20 use thereof is automatically restored to its operative position.

In the drawings forming a part of this application: Figure 1 is a diagrammatic side elevation of my starter in place on an automobile, only the front portion of the automobile being shown in dotted lines. Fig. 2 is a top plan of Fig. 1. Fig. 3 is a side elevation of my starter partly in longitudinal central section. Fig. 4 is a section on the 30 line 4-4 of Fig. 3. Fig. 5 is a section on the line 5-5 of Fig. 3. Fig. 6 is an enlarged sectional detail of the clutch pawl and adjacent parts.

Upon the front of the machine 9 is mounted 35 in any suitable manner a circular cup-shaped base plate 10 provided with a flange 11 on which flange are lugs 12. On the inside of the rim is an inwardly projecting stop lug 13. In the drawings I have shown 40 four of these outer lugs 12 of a semi-circular shape but there may be any desired number. Extending centrally through base plate 10 is a cranking shaft 14, on the inner end of 45 which is a coupling member 15, which couples onto the engine shaft. This coupling member is of such shape as will fit onto the engine shaft of the make of machine on which the starter is used. In the drawings this coupler is designed for attachment to a 50 Ford machine and the back of the base plate is also designed for use on that make of machine.

Mounted upon shaft 14 within the cup of the base plate is a rotary member composed 55 of two circular plates 16 and 17 which are spaced apart by a flange 18 at-

tached to one of the plates set at such distance from the edge as will form a chain groove around the rotary member. A portion of the edges of these plates are provided with projecting lugs 16^a and 17^a and when the parts are in their normal inoperative position these lugs engage lug 13 of the base plate. Between lugs 16^a and 17^a is mounted a pawl 19 by a pivoted bolt 20 which has a groove in its outer edge and is curved like the edges of the lugs of the plates. Below this pawl flange 18 is cut away so that the nose of pawl 19 can be brought into engagement with a ratchet 60 wheel 21 splined upon shaft 14 within the rotary member. A chain 22 is secured at one end by bolt 20 and passes through the groove in the back of the pawl and around the flange of the rotary member and out 65 through a port 23 in the base plate which lies in a plane substantially parallel with a plane that passes through the pawl longitudinally. The other end of the chain is fastened to one end of a cable 22^a the other end 70 of which is secured to a foot lever 24 mounted on the body of the machine in a position to be operated by the foot of the driver of the machine. The cable is guided by a suitable guide wheel 25 mounted on the body 75 of the machine. Secured to flange 18 is a flat spring 26 which projects beneath pawl 19 and normally holds the nose thereof out 80 of engagement with the ratchet wheel 21. Plate 17 has a hub 27 to which is secured 85 one end of a flat clock spring 28. The other end of spring 28 is secured to the inner side of a cup-shaped tension plate 29 which has notches 30 in its outer edge which fit over the lugs 12 of the base plate. By means 90 of this plate and the lugs on the base plate, spring 28 may be wound to give any desired tension. A cap plate 31 is secured to the base plate by screws 32 which also pass through holes 33 in the tension plate. In 95 the outer end of the cap plate is a removable cover 34 which when removed permits a cranking handle (not shown) to be placed on the end of shaft 14. A pin 35 in shaft 14 holds the crank against rotation on the 100 shaft. This pin and the cranking handle form another means of starting the engine.

With the parts properly positioned as shown the operation is as follows: The driver places his foot on lever 24 and gives 105 it a quick full movement. The initial part of the movement causes the chain to depress

the nose of the pawl into engagement with ratchet wheel 21 and the further movement causes the revolution of shaft 14 thereby cranking the engine. Should an explosion 5 not take place he releases the pressure on the foot lever when spring 26 throws the nose of the pawl out of engagement with the ratchet wheel and spring 28 returns the rotary member back to its starting point. He 10 then gives another quick push upon lever 24 and again cranks the engine. This is repeated until an explosion takes place. Usually the first cranking starts the engine. Should the engine backfire while the driver 15 is cranking the engine as before explained, the initial "kick" will cause the foot of the operator to be quickly and slightly thrown backwardly which releases the tension on chain 22 and immediately spring 26 will 20 throw the nose of the pawl out of engagement with the ratchet wheel and no discomfort or injury will be suffered by the driver. He then releases lever 24 and the parts are quickly returned to their normal position 25 ready to be again used for cranking.

Having described my invention what I claim is:

In an automobile starting device a cup-shaped base plate having lugs on the rim thereof, said base plate being adapted for 30 attachment on the body of the machine; an engine cranking shaft mounted in said plate; a rotary member loosely mounted on said shaft, said rotary member comprising two circular plates spaced apart by a flange 35 near the outer edges thereof, one of said plates having a hub, said plates and flange forming a housing; a notched wheel rigidly mounted on said shaft within said housing; a pawl mounted on said rotary member 40 adapted to contact with said notched wheel; a spring mounted on said rotary member adapted to hold said pawl out of contact with said wheel; a tension plate adjustably connected to said base plate; a clock spring 45 having one end secured to the hub of said rotary member and the other end secured to said tension plate; and a flexible connection secured to said rotary member whereby when the said flexible connection is pulled 50 the engine is cranked.

In witness that I claim the foregoing I have hereunto subscribed my name.

CHARLES POHL.
